(57) **CLAIM**

I claim the ornamental design for a flywheel of a stationary exercise machine, as shown and described.

DESCRIPTION

FIG. 1 shows a front isometric view of a flywheel of a stationary exercise machine in accordance with the present design.

FIG. 2 shows a rear isometric view thereof.

FIG. 3 shows a front view thereof.

FIG. 4 shows a rear view thereof.

FIG. 5 shows a right side view thereof.

FIG. 6 shows a left side view thereof.

FIG. 7 shows a top view thereof; and,

FIG. 8 shows a bottom view thereof.

(Continued)

The broken lines represent environment that forms no part of the claimed design.
